UNITED STATES PATENT OFFICE.

GEORGE EDMUND TURNER, OF MARION, OHIO.

STEAM DREDGE OR SHOVEL.

SPECIFICATION forming part of Letters Patent No. 627,662, dated June 27, 1899.

Application filed April 2, 1898. Serial No. 676,194. (No model.)

To all whom it may concern:

Be it known that I, GEORGE EDMUND TURNER, a citizen of the United States, residing at Marion, in the county of Marion and State 5 of Ohio, have invented certain new and useful Improvements in Steam Dredges or Shovels; and I do declare the following to be a full, clear, and exact description of the invention, such as will enable others skilled in the art to

10 which it appertains to make and use the same.

My invention relates to improvements in steam dredges or shovels; and the object is to simplify the construction and increase the speed, capacity, and general efficiency of the 15 device and at the same time provide a machine that can be properly and effectively controlled by a single hand, and thus dispense with the services of the other help usually employed on these machines.

20 To these ends the invention consists in the construction, combination, and arrangement of the device, as will be hereinafter more fully described, and particularly pointed out in the claims.

25 The accompanying drawings show my invention in the best form now known to me; but many changes in the details might be made within the skill of a good mechanic without departing from the spirit of the invention as set forth in the claims at the end 30 of this specification.

The same reference characters indicate the same parts of the invention.

Figure 1 is a plan view of my improved 35 steam shovel or dredge. Fig. 2 is a side elevation, partly in section, of the same. Fig. 3 is an enlarged schematic horizontal section of a portion of the operating mechanism. Fig. 4 is a detail perspective view of the hand- 40 lever. Fig. 5 is a detail of one of the clutch-collars.

1 denotes the base-frame or platform, which in the present instance is a platform-car mounted on suitable wheels traveling on a 45 track; but it may be the deck of a dredge or suitable barge when the shovel is used for submarine work.

2 represents the turn-table horizontally journaled to the forward end of the platform, 50 and 3 denotes the shoe or bracket in which the lower end of the crane 4 is fixed.

5 denotes the boom, which extends between the parallel arms of the crane and rests against a friction-roller 6, journaled in the crane, and 7 denotes the bucket fixed to the outer end 55 of the boom, and 8 represents its hinged door or bottom, provided with a spring-actuated latch 9, the rear end of which is pivoted to a lever 10, fulcrumed to the boom 5, and the outer end of this lever 10 is connected to a 60 rope 11, which passes over suitable guide-pulleys, and its free end is attached to the trip-weight 12.

13 represents the main driving-shaft, provided at one end with the balance-wheel 14 65 and at the other with the driving-pinion 15. The engine and boiler are not shown; but the engine-governor 16 is shown, which also forms the throttle-valve for the engine.

17 denotes the main hoisting-shaft, on 70 which the hoisting-drum 18 is loosely journaled.

19 denotes an eccentric fixed on one end of the shaft 17, and it is provided with the usual eccentric strap and rod 20, which operates the boiler-feed pump 21. 75

22 denotes a sprocket-wheel loosely journaled on said shaft 17, and its inner face is formed with a clutch 23, which is adapted to engage a corresponding clutch-collar 24, sliding on a key on the shaft. 80

25 represents a sprocket-wheel fixed on the car-axle 26, and 27 denotes a sprocket-chain connecting the sprocket-wheels 22 25, and by means of which the car may be propelled forward or backward, as desired. 85

28 denotes a collar loosely encompassing the shaft 17, contiguous to one end of the drum 18, and it is operated by the forked end of a lever 29, the free end of which is connected 90 by a rod 30 to a bell-crank lever 31, and from this latter a rod 32 extends to the lower end of the hand-lever 33. The opposite end of the drum 18 is formed with an integral concentric flange 34, the outer cylindrical face 95 of which is encompassed by a band-brake 35, controlled by a bell-crank lever 36, operated by a rod 37, connected to a bell-crank lever 38, from which a rod 39 extends to the piston-rod of a steam-cylinder 40, and the slide-valve 100 41 of this cylinder is provided with a valve-stem 42, extending to a bell-crank lever 43,

the opposite end or arm of which is connected to the rod 30, which, as above described, is operated by the hand-lever 33.

The inner face of the drum-flange 34 is formed with a female friction-cone 44, which encompasses a reversely-formed male cone 45, formed integral with the spur gear-wheel 46, fixed to the shaft 17 and in mesh with the pinion 15 on the engine-shaft 13, and when the collar 28 is employed to crowd the drum against the gear 46 the drum rotates with the gear, and when the collar is withdrawn the drum is released, and in the act of releasing the collar by means of the rod 30 the position of the valve 41 on the steam-cylinder 40 is reversed to actuate the rod 39 and apply the band-brake 35 to hold the drum stationary, so that the brake is automatically applied in the action of releasing the drum from its driving-shaft, there being of course sufficient lost motion between the cone-clutch on the drum and the brake so that the brake may be released while the clutch is out of gear.

From the drum 18 a chain or wire rope extends over suitable guide-pulleys, as shown, and over a guide-pulley 48 on the end of the boom 4, thence down around a pulley on the bucket-bail 50, and upward over a pulley 51 on the boom and down again, where its end is fixed to the shackle 52 on the bail 50.

53 represents a counter-shaft having a spur gear-wheel 54, fixed thereto and in mesh with the corresponding gear 46 on the shaft 17.

55 and 56 denote cone friction-hubs fixed on said shaft 53, and 57 and 58 denote winding-drums loosely journaled on said shaft, and their contiguous ends are formed with cone friction-flanges 59 60, which encompass the hubs 55 and 56, respectively.

61 and 62 represent collars loosely mounted on the shaft 53, contiguous to the outer ends of the drums 57 58, and they are adapted to move said drums endwise, so as to engage the friction-clutches 55 59 and 56 60, respectively.

45 The collar 61 is moved laterally to and from its drum 57 by means of the lever 63, the opposite end of which is connected to the bell-crank lever 64, which in turn is provided with a rod 65, extending to a similar bell-crank lever 66, from which a rod 67 extends to a hand-lever 68, while a collar 62 is similarly moved by a lever 69, connected to a bell-crank lever 70, the opposite arm of which is pivoted to the rod 65, the connections being such that

55 when the hand-lever 68 is thrown in one direction the drum 57 will revolve with the shaft 53, while the drum 58 is free, and, vice versa, when the hand-lever 68 is thrown in the opposite direction the drum 58 will be fast and

60 the drum 57 loose. A chain 71 has one end wound around and made fast to the drum 57, and after being carried around the turn-table 2 its opposite end is wound in the opposite direction and made fast to the drum 58, so that by the movement of the hand-lever 68 the crane 4 may be swung around to the right or left, as desired.

72 denotes a duplex friction-cone fixed on the shaft 53, and 73 74 represent winding-drums loosely journaled on said shaft on opposite sides of the cone 72, and their contiguous ends are formed with female cone-flanges, which are adapted to encompass the contiguous faces of the duplex cone 72.

75 76 represent collars loosely mounted on the shaft 53 adjacent to the outer ends of the drums 73 74, respectively, and they are adapted to be moved laterally on said shaft, so as to crowd either of the drums 73 or 74 against the cone 72, the collar 75 being moved to and from its drum by means of the lever 77, the outer end of which is pivoted to one arm of the bell-crank lever 78, which in turn is connected to the arm 79 of the bell-crank lever 80, and from the same arm a rod 81 extends 85 to a bell-crank lever 82, the opposite arm of which is pivoted to a similar bell-crank lever 83, and from the opposite arm of the said lever a rod 84 extends to another bell-crank lever 85, which in turn is connected to the hand-lever 33 by means of the rods 86 87 and bell-crank lever 88, so that a lateral movement in one direction of the lever 33 will lock the drum 73 to its shaft and simultaneously release the drum 74, and, vice versa, a lateral movement 95 in the opposite direction of the lever 33 will release the drum 73 and lock the drum 74 to its shaft. Of course it will be understood by reference to Fig. 5 that this lateral movement of the lever 33 in no wise affects the movement of the rod 32, the lever being fulcrumed on a "ball-and-socket" joint in the standard, although should occasion require to increase the speed, and consequently the capacity of the machine, the two movements may be effected simultaneously by a diagonal movement of the hand-lever.

89 denotes a chain which is wound over and its end fixed to the drum 73, and its opposite end passes over suitable guide-pulleys, as shown, and over a guide-pulley 90 on the crane 4, and its immediate end is fixed to the upper end of the boom 5. A similar chain 91 is wound under and its end fixed to the drum 74, and its opposite end, after passing over suitable guide-pulleys, as shown, and over the grooved pulley 92 on the crane, is made fast to the lower end of the boom 5, and by means of these chains 89 91 and the drums 73 74 the boom is manipulated as desired.

93 denotes a brake-band which encompasses the contiguous flanged ends of the drums 73 74, and it is controlled by the steam-cylinder 94, the piston-rod 95 of which is connected by a bell-crank lever 96 to a rod 97, which in turn is connected to the bell-crank lever 98, the opposite arm of which is pivoted to the brake-band 93.

99 represents the valve-stem of the cylinder 94, and its opposite end is pivoted to the common bolt 100, connecting the contiguous arms of the bell-crank levers 82 83, the operation being such that when either of the drums 73 74 are revolving the brake-band is

so adjusted as to bear on the flanges of the drums 73 74 with just sufficient friction to prevent the drums racing or the chains overrunning the chains on the drums.

5 101 represents a bell-crank lever, one end of which is connected to the governor-valve 16, (which, as hereinbefore stated, is also the throttle-valve,) and from the opposite arm of said lever a rod 102 is operatively connected 10 to a pedal 103, arranged convenient to the hand-levers 33 68, so that at the proper time the engine may be speeded to facilitate the work, thus placing the entire control of the machine to the best possible advantage of the 15 single attendant.

The hinged door 8 on the bucket 7 is automatically opened and closed in the ordinary operation of the boom 5 without any attention whatever on the part of the attendant 20 and is accomplished in the following manner: Assuming that the bucket has discharged its contents and the door is hanging open, the bucket is now given a rearward movement, which causes the door to fly to and the spring- 25 actuated latch to engage its keeper and lock the bucket-door. The length of the latch-rope 11 is such that it is always slack while the bucket is being lowered and raised, and at all times, in fact, except when the loaded 30 bucket is in an approximately vertical position and the boom 5 has been run outward to suspend the bucket over the dump, and the latch-rope is of such a length that the slack will be taken up and the strain come on the 35 weight 12 just before the boom reaches the outward limit of its stroke, thereby withdraw-

ing the latch and releasing the bucket-door, so as to permit the contents of the bucket to be discharged on the dump.

Having thus fully described my invention, 40 what I claim as new and useful, and desire to secure by Letters Patent of the United States, is—

1. The combination in a dredge, of the shaft 17, the drum 18, the brake-band 35 encompassing said drum, the steam-cylinder 40, having its piston-rod operatively connected to said brake-band 35, and means for simultaneously operating said piston-rod and connecting or disconnecting said drum and the 50 power-shaft, as and for the purpose set forth.

2. The combination in a dredge of the shaft 17, the drum 18 mounted on said shaft, the shaft 53, the drums 73, 74 mounted on the shaft 53, and the hand-lever 33, operatively 55 connected to said drums, 18 and 73, 74, as and for the purpose set forth.

3. The combination in a dredge, of the bucket 7, the door 8 hinged thereto, the spring-actuated latch 9, the lever 10 pivoted to said 60 latch, the flexible rope 11 connected at one end to said lever, the weight 12 fixed to the other end of said rope, and a shelf-support arranged in the path of said weight, substantially as and for the purpose set forth. 65

In testimony whereof I have hereunto set my hand in presence of two subscribing witnesses.

GEORGE EDMUND TURNER.

Witnesses:

LEWIS M. BRITTON,
HENRY TRUE.
